UNITED STATES PATENT OFFICE.

DAVID J. MC LAIRD, OF NASHVILLE, ARKANSAS, ASSIGNOR OF ONE-HALF TO JAMES L. TOLLETT, OF NASHVILLE, ARKANSAS.

SCREEN-BED.

1,119,621.

Specification of Letters Patent.

Patented Dec. 1, 1914.

Application filed March 31, 1914. Serial No. 828,504.

To all whom it may concern:

Be it known that I, DAVID J. MC LAIRD, a citizen of the United States, residing at Nashville, in the county of Howard and 5 State of Arkansas, have invented a new and useful Screen-Bed, of which the following is a specification.

The device forming the subject matter of this application is a screen for a bed.

10 One object of the invention is to provide novel means for assembling the screens detachably with the bed frame.

Another object of the invention is to provide a screen construction for a bed which 15 will give access to the bed either from the sides of the structure or from the top thereof.

It is within the scope of the invention to improve generally and to enhance the utility 20 of devices of that type to which the present invention appertains.

With the above and other objects in view which will appear as the description proceeds, the invention resides in the combination 25 and arrangement of parts and in the details of construction hereinafter described and claimed, it being understood that changes in the precise embodiment of the invention herein disclosed can be made 30 within the scope of what is claimed without departing from the spirit of the invention.

In the accompanying drawing: Figure 1 shows in perspective a screened bed embodying the present invention; Fig. 2 is a cross 35 section of the structure shown in Fig. 1; Fig. 3 is a perspective view depicting in spaced relation the elements whereby the side and top screens are pivotally connected with the head and the foot of the bed frame.

40 In carrying out the present invention there is provided a bed frame 1 which may be of any desired construction. The bed frame 1 comprises a head 2 and a foot 3, connected detachably by side rails 4, in the 45 well known manner. The side rails 4 may support slats 5 upholding the mattress 6, the specific means for supporting the mattress 6, however, being largely immaterial, so far as the broad features of the invention 50 are concerned.

Although the bed frame 1 may be of any desired form, the same when constructed especially for the purpose hereinafter described, may be equipped in its head and 55 foot portions 2 and 3 respectively with

screens 7. These screens, like all of the screens hereinafter described, may be made of any desired material.

The invention further includes a pair of side screens 8 and a pair of top screens 9, 60 all of which are provided with suitable handles 10 of any desired construction. Located upon the side screens 8 adjacent their upper edges are hinge plates 12 and located upon the top screens 9 adjacent their outer edges are hinge plates 11. Through 65 the knuckles of the hinge plates 12 and 11 extend pivot elements 14, provided terminally with enlarged heads 15. In the head 2 and in the foot 3 adjacent the outer edges 70 thereof are formed recesses 16 across which extend keepers 17 preferably in the form of plates. In the keepers or plates 17, curved slots 18 are formed; each slot 18 at its inner end being provided with an opening 19 which is large enough to receive the head 15 of the pivot element 14, the slot 18 being restricted in diameter and being narrower than the diameter of the head 15. In the outer end of each slot 18 a journaling 75 notch 20 is formed.

In practical operation, the pivot elements 14 are inserted into the slots 18 through the openings 19 and then are slid outwardly, until the pivot elements 14 ride rotatably 80 in the journaling notches 20. Then the side rails 4 are connected with the head 2 and the foot 3 to prevent these elements from spreading apart. When the top screens 9 and the side screens 8 are thus supported 85 upon the bed frame 1, the side screens 8 hang in pendant positions between the head 2 and the foot 3 and above the side rails 4, the top screens 9 being horizontally disposed and being supported upon cleats 21 90 which are secured to the head 2 and the foot 3. When the parts are positioned as above described, the occupant of the bed will be completely screened in and noxious insects 95 will be shut out.

100 It is to be observed that the top screens 9 may be swung outwardly and may rest against the side screens 8, access thus being afforded to the bed from the top thereof. If desired, however, the side screens 8 may be 105 swung upwardly and inwardly and may rest upon the top screens 9, the bed being thus opened at the sides. The feature last above mentioned is of peculiar utility when it is desired to change the bedding. All of the 110

screens 8 and 9 open outwardly, and thus the occupant of the bed can readily create an exit at any time. When the top screens 9 are folded against the side screen 8 these elements may be swung around in a complete circle with the pivot elements 14 as a center, saving in so far as prevented by the cleats 21.

Having thus described the invention, what 10 is claimed is:—

1. In a device of the class described, a bed frame comprising a head and a foot; a pair of top screens and a pair of side screens, each top screen and one side screen having a 15 common pivotal connection with the head and the foot adjacent the outer edge of the frame, whereby the side screens may be

swung upwardly and inwardly to rest upon the top screens, and whereby the top screens may be swung downwardly and outwardly 20 to rest against the side screens.

2. In a device of the class described, a bed frame; a top screen; a side screen; pivot elements connecting the top screen with the side screen; and means upon the frame for 25 receiving the pivot elements thereby to afford a support for both screens.

In testimony that I claim the foregoing as my own, I have hereto affixed my signature in the presence of two witnesses:

DAVID J. McLAIRD.
